UNITED STATES PATENT OFFICE.

THOMAS EDMUND HOLMES, OF GLASGOW, SCOTLAND.

COGGING AND LIKE MILL FOR TIRES.

1,357,055.

Specification of Letters Patent. Patented Oct. 26, 1920.

Application filed October 1, 1919. Serial No. 327,820.

To all whom it may concern:

Be it known that I, THOMAS EDMUND HOLMES, a subject of the King of Great Britain and Ireland, and a resident of Glasgow, Scotland, have invented certain new and useful Improvements in Cogging and like Mills for Tires, of which the following is the specification.

The invention relates to cogging and like mills, for tires, of the type in which the axes of the rolls are horizontal, the movable roll being arranged to move parallel by a parallel motion device; and has for its object to provide a simple and effective mill in which the scale and other matters falling freely from the rolls do not clog the mechanism—thus stoppage of the mill for their removal is obviated.

In carrying out the invention the rolls are arranged in vertical plane with their axes horizontal. They are carried as usual in housings with their tire-forming parts adjacent and overhanging the housings in opposite directions.

According to the invention the upper roll is movable vertically, its bearing blocks being guided in vertical guides in its housings. It is constrained to move parallel by a parallel-motion linkage arranged above the roll and is moved to adjust the tire gap and during rolling by hydraulic means applied to the bearing block adjacent to the pass. Both rolls are driven—the lower roll directly; the upper and movable roll through a shaft universally jointed to the roll and to the driving means.

An example of the carrying out of the invention is illustrated in three accompanying sheets of explanatory drawings, Figure 40 1, Sheet 1 being a side elevation, Fig. 2 Sheet 2 an end elevation and Fig. 3 a plan.

In this example, the upper roll A is movable vertically, its bearing blocks B being guided in vertical guides in housings C. Its 45 movements are constrained to be parallel

with one another by a linkage consisting of two armed bell-crank levers D, E, one arm of each of which is connected to a bearing block B by a link F, while the other arms are interconnected by a link G. The bell-crank levers D, E are pivoted upon a bracket H mounted on the framing transom J.

The roll A is moved vertically to adjust the rolling gap by a hydraulic ram K operatively connected to the bearing block B adjacent to the gap and moving in a hydraulic cylinder L supported on the housing C.

Both rolls are driven, the upper and movable roll A by way of a shaft A' and a doubly universally jointed shaft M from a usual driving train (not shown) and the lower roll N (supported in housings O in usual manner) by way of a shaft P from a usual driving train (not shown).

It will be seen that with this arrangement the mechanism for operating the movable roll A is entirely above the pass and away from falling scale and the like, which also falls clear of the lower roll N the driving mechanism of which is not beneath its level.

What I claim is:—

In a cogging or like mill for tires having rolls arranged in vertical plane with their axes horizontal and their tire forming parts adjacent and overhanging the housings in opposite directions; an upper roll movable vertically in guides, means for maintaining parallelism of the roll throughout its movements, means for moving the roll to adjust the pass and applied adjacently thereto and means for driving the roll, the operating mechanism for the upper roll and the means for maintaining parallelism being disposed above the pass and clear of falling scale from the rolls, as set forth.

In testimony whereof I have signed my name to this specification.

THOMAS EDMUND HOLMES.
